UNITED STATES PATENT OFFICE.

JOHN H. GILES AND DONALD M. GILES, OF TAUNTON, MASSACHUSETTS.

DYEING-MACHINE.

1,146,324.

Specification of Letters Patent. Patented July 13, 1915.

Original application filed December 29, 1913, Serial No. 809,177. Divided and this application filed August 28, 1914. Serial No. 859,033.

To all whom it may concern:

Be it known that we, JOHN H. GILES and DONALD M. GILES, citizens of the United States, residing at Taunton, in the county of 5 Bristol and State of Massachusetts, have invented new and useful Improvements in Dyeing-Machines, of which the following is a specification.

This invention relates to machines for the 10 dyeing of yarns and the like and consists of an improved adjusting mechanism for the series of yarn supporting sticks. This improved adjusting mechanism of our invention operates simultaneously to adjust all of 15 the inner stick bearings with relation to the outer series of sticks and is of a character wherein removable securing parts are not required and, moreover, it is adapted to be actuated by a removable wrench thereby 20 to afford a cool operating handle for the operator. Our present invention is particularly adapted to the type of machine shown in our application Ser. No. 809,177 filed December 29, 1913, of which the present application is a division.

The aforesaid and other features and advantages will be understood by reference to the accompanying drawings and description wherein the reference numerals of the 25 description are applied to like parts in the several views.

In the drawing, Figure 1 is a vertical cross-sectional view of a machine constructed to embody the features of this invention; 30 Fig. 2 is a vertical longitudinal sectional view of the same and Fig. 3 is a partial detail view in left side elevation showing the rack and worm arrangement.

Referring to the drawings, the machine 35 comprises the dye-tub or vat 1 containing the dye liquor substantially to the level shown. In bearings 2-2 at the ends of the tub is journaled a central supporting shaft 3 having fixed thereon within the tub the 40 spiders 5 the spokes 5 thereof supporting the outer and inner bearing rings 6 and 7. The bearing rings are oppositely arranged and provided with bearings for the outer and inner series of longitudinally arranged 45 50 yarn supporting sticks 10 and 11 respectively. The skeins of yarn to be dyed are

suspended between the sticks of the outer and inner series or double reels in the manner indicated in dotted lines in Fig. 1 and upon revolving the rotary carrier formed 55 by the spiders and sticks the yarn is carried downwardly through the dye liquor. Any suitable means, such as external gearing, may be employed to rotate the shaft 3 and with it the supported skeins of yarn 60 but such driving connections are not necessary to be here shown.

The yarn sticks are supported in the bearing rings 6 and 7 in a manner to permit of periodically changing the position of the 65 yarn on the sticks in the customary manner. To that end the outer series of sticks are shown fitted to suitable socket bearings 16 at one end and to bearing apertures in the outer rings at their opposite ends. The 70 socket bearings 16 are journaled in the central outer bearing ring and are shown provided with sockets on each side to receive the ends of yarn sticks arranged in parallel alignment. Each of the journaled socket 75 bearings 16 has thereon a star wheel 18 to be engaged by a suitably supported trip device 7 on each revolution of the sticks whereby a quarter turn of the bearing and the yarn stick is effected so that the position 80 of the yarn on the sticks is being constantly changed during the dyeing operation.

As best shown in Fig. 2, the outer ends of the outer yarn sticks are entered into bearing apertures 20 in the bearing rings 85 and to permit of the entry of the sticks into the sockets they are formed with elongated reduced or ferrule portions 21 which permit of a slight longitudinal movement of the sticks sufficient for entering their ends into 90 the sockets. When so positioned means are provided for retaining them against withdrawal during the operation of the machine. This means is shown consisting of a retaining rail 38 secured on the side of the 95 tub in position to engage the ends of the sticks so as to retain them within the sockets and it is provided with a hinged gate portion 38' which is removable from retaining position to permit of inserting and with 100 drawing the sticks.

The bearings for the inner series of sticks

may be of any approved form and are indicated of a customary type of bearing provided by flanges 88 on the inner rings 7 having openings to admit the sticks which are retained within the bearing sockets so provided by suitable hinged covers 90.

The stick adjusting mechanism of the present invention has for its purpose to adjust the distance between the outer sticks 10 and the inner sticks 11 best to suit the length of the skeins on the sticks. For that purpose, in the embodiment of our invention here illustrated, it is arranged that the inner stick bearing rings are rotatively supported 15 on the spiders S. The inner rings 7 are thus permitted to have a movement relative to the outer bearing rings which are rigidly supported on the spiders. The bearings upon which the inner stick bearing rings 7 20 turn are provided as shown by the ends of the inner reinforcing ribs of the spokes 5. Suitable clips 75 on the spokes engage the outer edges of the rings to hold them in position. The two inner bearing rings at the 25 center of the double type of machine shown are desirably secured together by bolts or otherwise so that they will turn together thus forming a double bearing ring.

For turning of the rings they are provided 30 on their inner peripheries with racks or toothed segments 76. Engaging the teeth of these racks 76 are pinions 83 carried on a longitudinally arranged shaft 80 which is journaled in suitable bearing brackets 78 35 carried on the spokes 5. A worm gear 81 is provided on the end of the shaft 80 whereby it is turned to shift the bearing rings 7 through the engagement of the pinions and racks and thus shift the entire series of inner stick bearings and the sticks in unison. Conveniently to effect this movement we 40 have provided a radially arranged actuating shaft 84 journaled in suitable brackets 78 and 85 on the spokes and the outer ring 6. Upon the actuating shaft is arranged a worm 45 86 in engagement with the worm gear 81. The outer end of the actuating shaft 84 is squared for the engagement of a suitable detachable operating wrench by the operation of which all of the inner bearing rings 50 and sticks will be moved together with relation to the outer yarn sticks. In employing the worm 86 to effect the adjustment of the sticks detachable securing means to retain 55 the parts in adjusted position are not required for the worm and worm gear are self locking and retain the connections in any position as adjusted. Furthermore, the arrangement described adjusts all of the bearings 60 in one operation and the use of the detachable wrench affords a cool handle for the operator.

Other features of the machine shown in Fig. 1 are the dye receptacle 124 from which

the dye liquor is admitted into the vat 65 through a dye distributing pipe 126; the false back or baffle 103 behind which the steam is admitted under pressure to maintain proper circulation of the dye and to heat it and 102 indicates the steam distributing pipe through which the steam is introduced to the tank from the steam pipe 100.

Having described our invention, we claim

1. A dyeing machine having an inner and 75 an outer set of stick supporting members and means for simultaneously adjusting the relation of one set with reference to the other comprising racks carried by the members of one set, an actuating shaft journaled 80 on the other members, pinions on the actuating shaft in engagement with the racks, a worm gear on said shaft, an operating shaft on a member of the latter set and an operating worm on the operating shaft in 85 operative engagement with the worm gear.

2. A dyeing machine having an inner and 90 an outer set of annular stick supporting members, the inner of said members being journaled to move relative to the outer members, 95 racks on the inner members, an actuating shaft carried by the outer members, pinions on the actuating shaft in mesh with the racks, a worm gear on the actuating shaft, a radially arranged operating shaft suitably 100 journaled and an operating worm on said shaft in engagement with the worm gear to effect simultaneously the adjustment of the inner supporting members relative to the outer supporting members for varying the 105 distances between the sticks.

3. A dyeing machine having an inner and 110 an outer set of annular stick supporting members, the inner of said members being journaled to move relative to the outer members, racks on the inner members, an actuating shaft carried by the outer members, pinions on the actuating shaft in mesh with the racks, a worm gear on the actuating shaft, a radially arranged operating shaft 115 suitably journaled and an operating worm on said shaft in engagement with the worm gear to effect simultaneous adjustment of the inner supporting members relative to the outer supporting members and a squared 120 end portion on the operating shaft for the application of a detachable wrench substantially as described.

4. A dyeing machine having an inner and 125 an outer set of stick supporting members and means for simultaneously adjusting the relation of one set with reference to the other comprising racks carried by the members of one set, an actuating shaft journaled on the other members, pinions on the actuating shaft in engagement with the racks, a worm gear on said shaft, a radially arranged operating shaft on a member of the

latter set, an operating worm on the operating shaft in operative engagement with the worm gear and a squared end portion on the operating shaft for the engagement therewith of a detachable wrench for manually adjusting the position of the parts.

5 In testimony whereof we have signed our

names to this specification in the presence of two subscribing witnesses.
